David B. Pieper(57) **CLAIM**

The ornamental design for a front viewing removal slot package display, as shown and described.

DESCRIPTION

FIG. 1 is an unfolded view of a front viewing removal slot package display showing my new design;

FIG. 2 is a perspective view thereof;

FIG. 3 is a cutaway perspective view showing internal features viewable through the open apertures.

FIG. 4 is a front view thereof; and,

FIG. 5 is a back view thereof;

FIG. 6 is a left side view thereof;

FIG. 7 is a right side view thereof;

FIG. 8 is a top view thereof; and,

FIG. 9 is a bottom view thereof.
